Primary Examiner — Robert M. Spear

(57) **CLAIM**

The ornamental design for a control lever, as shown and described.

DESCRIPTION

FIG. 1 is a perspective view of a control lever showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the claimed design of FIGS. 1-7 in a use environment.

The broken lines illustrate structure or features which form no part of the claimed design.
